(57) **CLAIM**

The ornamental design for an articulator plate as shown and described.

DESCRIPTION

FIG. 1 is a front isometric view of an articulator plate.

FIG. 2 is a front side elevation view thereof.

FIG. 3 is a back side elevation view thereof.

FIG. 4 is a left side elevation view thereof.

FIG. 5 is a right side elevation view thereof.

FIG. 6 is a top side plan view thereof.

FIG. 7 is a bottom side plan view thereof; and,

FIG. 8 is a top isometric view of the articulator plate in a lab scanner.

The features shown in broken lines in the drawing portions of the articulator plate that form no part of the claimed design. The broken lines depicting the lab scanner in FIG. 8 represent environmental subject matter and forms no part of the claimed design.

1 Claim, 8 Drawing Sheets
